UNITED STATES PATENT OFFICE.

TAAVI HELSKE, OF SAN FRANCISCO, CALIFORNIA.

SWITCH BOX.

1,424,407.

Specification of Letters Patent. Patented Aug. 1, 1922.

Application filed May 28, 1918. Serial No. 237,357.

To all whom it may concern:

Be it known that I, TAAVI HELSKE, a citizen of the United States, residing at the city and county of San Francisco, State of California, have invented certain new and useful Improvements in Switch Boxes, whereof the following is a specification.

This invention relates to electric switch boxes, and its object is to promote the cause 10 of safety.

To this end I so construct a switch box that the opening thereof automatically cuts off the electric current, so that the operator, or meddler, is in no danger therefrom.

15 In carrying out the invention, I, by preference, provide the switch box with a lid, or door, opening outward, and I connect this door with the switch so that the opening of the door automatically throws the 20 switch, and cuts off the current. I also provide the box with a partition extending between the part opened by said cover and the switch which prevents the insertion of the fingers, or other objects; said partition, 25 or guard, is connected to another cover or removable lid which may be opened to give 30 to access to the switch, if desired, but which, ordinary, is not noticeably openable, and hence is not likely to be opened inadvertently, or by a meddler.

In the accompanying two sheets of drawing I have illustrated a switch box constructed as above suggested, and containing my invention in what I now consider its 35 best form.

Figure 1 is a sectional side view, with the cover closed.

Figure 2 is a similar view, but with the cover open.

40 Figure 3 is a front view with the cover open.

In these figures: The body of the box is represented by the reference numeral 1. 2 is a partial cover for the front thereof, 45 carrying an inward projecting guard 3, which together virtually enclose the switch 4. The cover 2 may be secured to the box in any suitable manner, as by projections on the one entering depressions in the other, 50 as at 5. The cover 6, which encloses the part of the box not protected by the members 2 and 3, may be hinged at 7, and swing

outward and downward, as clearly seen in Figure 2. 8 is a knob upon the cover 6, for convenience in the manipulation of the same, 55 and 9 is a latch, pivoted at 10 to the member 2, and engaging the edge of cover 6 to maintain the same in its closed position.

The switch, generally denoted by the reference letter 4, is conventionally shown as 60 of the ordinary swinging knife blade form, and need not be further described. It is mounted on a suitable base 12, which may also support fuse plugs 13, which base is attached to the bottom of the box 1. A 65 standard 14 is attached to the switch knives 4, and is connected by a bar 15 with a similar standard 16 projecting inward from the cover 6, whereby the opening of the cover 6 automatically opens the switch, as clearly 70 seen in Figure 2. The bar 15 passes through a kerf 17 in the guard plate 3, and the latter serves not only as a guard but also as a stop for the switch knives to prevent their opening beyond the required or desired degree, 75 and may serve also as a stop for cover 6.

From the foregoing it is clear that the opening of the box automatically opens the switch, thereby turning off the current, and making it safe for the operator to further 80 open the box, and expose the switch, if such be desired, but the switch cannot be exposed by the removal of the member 2 without first opening cover 6 and throwing the switch, owing to the lip 18 on member 2 85 engaging the under side of cover 6 and inward guard 3, which is a part of lip 18.

Having thus described my invention, and an embodiment of it, in the full, clear and exact terms required by law, and knowing 90 that it comprises novel, useful and valuable improvements in the art to which it pertains, I here state that I do not wish to be limited to the precise construction and arrangement of the several parts, as herein 95 set forth, as the same may be variously modified by a skilled mechanic without departing from the spirit of the invention.

What I claim and desire to secure by Letters Patent of the United States, is the 100 following, to-wit:

A switch box containing a switch, a cover for said box comprising a removable portion and a hinged portion, a guard project-

ing from said removable portion forming thereby an inclosure for said switch, said hinged portion being connected to said switch and adapted to operate the same, 5 frictional means adapted to secure said removable portion to said box and means to lock said hinged portion to said removable portion.

In testimony, that I claim the foregoing I have hereto set my hand in the presence 10 of two witnesses, this 23 day of May, 1918.

TAAVI HELSKE.
